UNITED STATES PATENT OFFICE.

CHARLES L. McCUEN, OF DETROIT, MICHIGAN, ASSIGNOR, BY MESNE ASSIGNMENTS, TO
DELCO-LIGHT COMPANY, OF DAYTON, OHIO, A CORPORATION OF DELAWARE

REFRIGERATING APPARATUS.

Application filed October 9, 1918. Serial No. 257,437.

To all whom it may concern:

Be it known that I, CHARLES L. McCUEN, a citizen of the United States, and resident of Detroit, Wayne County, State of Michigan, have invented certain new and useful improvements in Refrigerating Apparatus, of which the following is a specification.

This invention relates to refrigerating apparatus and particularly to that type of apparatus that is adapted to be used in connection with household refrigerators.

One of the objects of the invention is to provide a compact arrangement of the refrigerating apparatus.

Another object of the invention is to provide the compressor, condenser, and motor units with interconnections of simple and compact form.

Another object of the invention is to provide a refrigerating apparatus which is adapted to have all of its parts mounted or supported upon a single base so that it may be readily associated with a refrigerator.

Another object of the invention is to construct the base of the unit so that a storage chamber for the refrigerant may be housed within it.

Other objects of the invention will appear from the following description taken in connection with the drawings which form a part of this specification, and in which:

Figure 1 is a vertical section through the upper part of a refrigerator and a refrigerating apparatus built in accordance with this invention mounted thereon, some of the parts being in elevation; and

Figure 2 is a vertical section at right angles to Figure 1, on line 2—2 of Figure 1.

Referring to the drawings, 10 represents a refrigerator of the ordinary domestic type, having a compartment 11 which is usually an ice compartment. An opening 12 is provided in the top wall of the refrigerator over the compartment 11 and an expansion coil 13 of suitable form is arranged to be inserted through the opening 12 into the compartment 11. This coil 13 is supported by brackets 14 which are secured to a base 15 forming the principal support and foundation of the refrigerator unit or apparatus.

As shown, this base 15 is of hollow form, being open at the bottom and arranged on the refrigerator 10 so that its interior is open to the compartment 11 through the

opening 12. It will be understood that the base 15 rests upon the refrigerator, being detachably secured thereto if desired, and it may be readily removed with the parts attached to it including the expansion coil 13, 60 which may thereby be withdrawn through the opening 12.

Supported upon the base 15 is a compressor 16 shown as having two upright cylinders 17, a crank shaft 18 with cranks 19, 65 connecting rods 20 and pistons 21. The compressor also comprises a crank case 22 which surrounds the operating parts of the compressor and a worm gear 23 operates in the crank case and is secured to the middle 70 part of the crank shaft as shown particularly in Figure 2. The worm gear 23, and consequently the crank shaft 18, is driven by a worm 24 on a driving shaft 25, which shaft is mounted in bearings 26 and 27 in 75 the crank case. The driving shaft 25 extends through the wall of the crank case and is surrounded by a packing 28 to prevent leakage therefrom.

A motor 29, preferably an electric motor, 80 is supported by a bracket 30 on the base 15 and it is connected by a suitable joint 31 to the driving shaft 25 so that it will operate the compressor through said crank shaft and the gears 23 and 24. 85

It will be noticed that the shaft 25 is beneath the gear 23 in the lower part of the crank case 22 so that it will be lubricated by the oil within the crank case. It will also be seen that the crank case fully encloses 90 the operating parts of the compressor and that a pipe 32 connects with the crank case, leading from the expansion coil 13 above referred to. A by-pass 33, shown in Figure 1, is provided in the side wall of each of 95 the cylinders and a port 34 opens into the cylinder substantially at the lowest point of travel of the piston 21. Thus it will be understood that as the piston moves downwardly a vacuum will be created in the cylinder until the piston uncovers the port 34. This will cause a suction from the crank case and consequently from the expansion coil 13 through the pipe 32, for purposes 100 hereinafter more fully described. 105

Mounted very close to the compressor and at one side thereof is a condenser 35 which comprises a casing 36 and a series of pipes 37 within the casing. The inlet end of the condenser is connected with the outlet of 110

the compressor by a pipe 38, and preferably a check valve 39 is arranged, as shown in Figure 1, at the inlet end of the condenser. Also, each of the cylinders 17, at its 5 outlet end, is provided with a check valve 40 which is spring closed on the downward stroke of the piston.

For the purpose of increasing the circulation of air around the pipes 37 of the condenser, a fan 41 is arranged between the condenser and compressor. This fan draws air through the condenser, and therefore around the condenser pipes, and likewise increases the circulation of air around the 10 flanged cylinders of the compressor.

The fan is mounted on a shaft 42 which extends laterally between the cylinders 17 and is mounted in bearings 43, 44 in the crank case casting. A connection for driving the fan shaft is provided in the form of a belt 45 operating on pulleys 46 and 47 on the driving shaft 25 and the fan shaft 42 respectively.

The outlet from the condenser 35 connects 25 through a pipe 48 to a storage chamber 49.

This chamber is in the form of a circular coil of pipes and is arranged within the hollow base 15 directly beneath the compressor 16. It is thus more or less subjected 30 to the cool air of the compartment 11 so that the refrigerant in its condensed state is more readily retained.

The outlet from the storage chamber 49 is through an expansion valve 50 of any 35 suitable type, to the expansion coil 13. This valve permits the flow of refrigerant through it into the expansion coil 13 as the pressure within that coil is reduced below a given pressure.

40 Also suspended from the support 15 is a thermostat 51, preferably of the elongated type, that extends down through an opening in the expansion coil 13. The upper end of this thermostat extends into the space 45 surrounded by the coils of the pipe forming the storage chamber 49, as shown in Figure 1, thus economizing in space. The thermostat shown comprises an upright bracket 52 having separated contacts 53 and 54, a swinging hammer switch 55 pivotally supported at 56, a rigid arm 57 extending downwardly from the bracket 52, and a U-shaped thermostat 58 the upper arm 59 of which is bifurcated as at 60 so that it extends on both sides 50 of the lower extremity of the hammer switch 55. The adjustable points 61 of the arm 59 are adapted to contact with the sides of the switch 55 as the thermostat arm 59 is moved laterally (in Figure 1) by the thermostat proper, to thereby shift the switch from one position to the other or from one contact 53, 54 to the other. In Figure 1 the switch 55 is shown as resting on the contact 53 and as the arm 59 of the thermostat 60 is moved to the right it will be seen that the

upper end of the switch 55 will be shifted so that it will rest against the contact 54. A reversal of the thermostat arm 59 will of course reverse the operation of the switch. Thus the differences in temperature in the 70 compartment 11 that affect the thermostat 58 will operate the switch 55 to thereby start or stop the motor that operates the compressor.

Not all of the operating connections between the thermostatically operated switch 75 and the motor 29 are shown, but it will be understood that a battery such as indicated at 62, in Figure 1, is connected as by a wire 63 to the switch 55 and two wires 64 and 65 80 extend from the contacts 53 and 54 respectively to suitable solenoids and starting mechanism such, for instance, as is shown at 66 in somewhat conventional form. This starting mechanism may be of any suitable 85 form for starting and stopping the motor 29 upon contact of the switch 55 with one or the other of the contact points 53, 54.

The refrigerating apparatus above described is intended preferably to operate 90 with sulphur di-oxide (SO_2) or a similar refrigerant, and it will be understood that upon operation of the compressor by the motor 29 the expanded refrigerant gaseous form in the expansion coil 13 will be withdrawn through the pipe 32 and the crank case 22. The compressor will operate to considerably raise the pressure of the refrigerant and pass it through the valves 40 and 39 into the condenser 35. Here the refrigerant, under pressure, passes through the coils 37 and is condensed to liquid form. It is passed to the pipe 48 in the storage chamber or coil 49 for use as required. As the temperature in the compartment 11 rises 100 above a given point the thermostat 51 expands and operates the switch 55 to cause the starting mechanism 66 to start the motor 29. This sets the compressor in operation and withdraws the refrigerant from the expansion coil 13 and thereby reduces the pressure therein. This reduction of pressure, when it reaches a given point, causes the automatic operation of the expansion valve 50 so that the refrigerant is fed 105 through that valve into the expansion coil where it rapidly expands and thereby produces a reduction in temperature in the coil. The apparatus then operates until the temperature within the compartment 11 drops below a given point when the thermostat 51 operates the switch 55 to close the circuit through the contact 53 and, through the starting mechanism 66, stops the motor 29. Of course this operation is repeated as 110 often as the temperature in the compartment 11 rises above the point set for it.

But a single form of the invention has been shown and described herein. It will be understood, however, that other forms 115

and modification may be made without departing from the spirit or scope of the invention as set forth in the appended claims.

Having thus described the invention what

5 I claim and desire to secure by Letters Patent is:—

1. In a refrigerating apparatus, in combination, a support, a compressor thereon, a condenser on one side of the compressor and 10 a motor on the other side thereof, a fan disposed on the same side of the compressor as the condenser to operate in connection with the condenser, and connections for operating the compressor and fan from the 15 motor.

2. In a refrigerating apparatus, in combination, a support, a compressor thereon, a condenser on one side of the compressor and a motor on the other side thereof, a 20 fan mounted on the compressor and having a shaft extending from one side to the other thereof, and connections for operating the compressor and said shaft from the motor.

25 3. In a refrigerating apparatus, in combination, a two-cylinder compressor, a fan shaft extending laterally between the cylinders, a motor, and connections for driving the compressor and fan shaft from the 30 motor.

4. In a refrigerating apparatus, in combination, a two-cylinder compressor, a fan shaft extending laterally between the cylinders above the crank shaft of the 35 compressor, a motor, a driving shaft from the motor to the compressor arranged beneath the crank shaft, and connections for driving the fan shaft from the motor.

5. In a refrigerating apparatus, in combination, a hollow support, a compressor and condenser, means for driving the compressor, a storage coil in the support, and a thermostat extending into said coil.

45 6. In a refrigerating apparatus, in combination a hollow support, a compressor and condenser, means for driving the compressor, a storage coil in the support, an expansion coil arranged beneath the storage coil, and a thermostat in the expansion coil 50 and extending into the storage coil.

7. In a refrigerating apparatus, in combination, a two-cylinder compressor having a worm wheel and cranks at the sides of the worm wheel, a worm and driving shaft

arranged beneath the worm wheel, a fan 55 shaft parallel to the driving shaft above the worm wheel, and means for driving the driving shaft and fan shaft.

8. In a refrigerating apparatus, in combination, a two-cylinder compressor having 60 a worm wheel and cranks at the sides of the worm wheel, a worm and driving shaft arranged beneath the worm wheel, a fan shaft parallel to the driving shaft above the worm wheel, and means for driving the 65 fan shaft from the driving shaft.

9. In a refrigerating apparatus, in combination, a two-cylinder compressor having a worm wheel and cranks at the sides of the worm wheel, a worm and driving shaft 70 arranged beneath the worm wheel, a fan shaft parallel to the driving shaft above the worm wheel, a motor connected to the driving shaft, and driving connections from the driving to the fan shaft.

75 10. In a refrigerating apparatus, the combination with a refrigerator having an opening, a support mounted over said opening, said support having a chamber therein provided with an opening extending substantially over one entire side of the chamber and registering with said opening in the refrigerator, an expansion coil suspended from the support within the refrigerator, and a liquid-refrigerant storage chamber 80 connected to said coil and comprising horizontally disposed means in said first-mentioned chamber for receiving the liquid refrigerant therein.

11. In a refrigerating apparatus, the combination with a refrigerator having an opening, a support mounted over said opening, said support having a chamber therein provided with an opening extending substantially over one entire side of the chamber 85 and registering with said opening in the refrigerator, a compressor and condenser mounted on the support, a liquid-refrigerant storage chamber comprising horizontally disposed means in said first-mentioned 90 chamber for receiving liquid refrigerant therein, and an expansion coil suspended from the support within the refrigerator, said expansion coil forming a unit with the support adapted to be inserted or with- 95 drawn through said refrigerator opening.

In testimony whereof I affix my signature.
CHARLES L. McCUEN.
